[57] CLAIM

The ornamental design for a household product holder, as shown and described.

DESCRIPTION

FIG. 1 is a front, right side, and top perspective view of a first embodiment of a household product holder showing my new design. This embodiment is adapted to hold a roll of toilet paper;

FIG. 2 is a top plan view thereof;

FIG. 3 is a front elevation view thereof;

FIG. 4 is a bottom plan view thereof;

FIG. 5 is a right side elevation view thereof;

FIG. 6 is a left side elevation view thereof; and,

FIG. 7 is a rear elevation view thereof.
